UNITED STATES PATENT OFFICE.

GLADYS RUSH, OF LONGMEADOW, MASSACHUSETTS.

DOLL.

Application filed November 13, 1925. Serial No. 63,842.

This invention relates to toy dolls, and has for its object to provide, in a manner as hereinafter set forth, an unusually attractive doll of the flat type and which is practically indestructible, as well as permitting of the same to be easily packed in a small space within a travelling case.

A further object of the invention is to provide, in a manner as hereinafter set forth, a toy doll of the flat type, having means to permit of the garments as well as the hat therefor to be sewed to any portion of the front or back of the doll body for the purpose of retaining the same in position.

Further objects of the invention are to provide, in a manner as hereinafter set forth, a toy doll of the flat type, which is simple in its construction and arrangement, strong, durable, attractive in appearance, and inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a front elevation of a toy doll in accordance with this invention.

Figure 2 is a front elevation, broken away, of the doll body and further illustrating the hair positioned on the head and the slippers upon the feet.

Figure 3 is a section on line 3—3, Figure 2.

Figure 4 is an elevation of one of the slippers.

The body portion of the doll is referred to generally by the reference character 1, is flat throughout and consists of a base 2 of paper stock having secured throughout to each face thereof a fabric covering 3, 4. The base 2, as well as the coverings 3, 4, is of corresponding contour and shaped to provide a head 5, neck 6, arms 7, hands 8, body 9, legs 10 and feet 11.

The fabric coverings 3, 4 reinforce the base 2, under such conditions providing a practically indestructible body portion 1.

The fabric coverings 3, 4 permit of the

dress 12 and hat 13 to be secured therewith by stitching to normally prevent the removal thereof when placed in position.

That portion of the covering 3, at the head 5, is provided with the representation of a mouth 14, nose 15, eye openings 16, eye balls 17, and eye lashes 18, and these several representations are formed by threads secured to the fabric covering 3 and disposed in the desired manner. The threads are of a different color from the fabric covering 3. The fabric covering 3 can be suitably colored or tinted, as at 19, to represent rosy cheeks.

Positioned against the edge of the head 5, as well as overlapping the front and rear marginal portions thereof, is a mass of hair 20, which projects from the hat 13 when the latter is secured in position. The hat 13 is provided with tie strings 21.

Mounted on each foot portion 11 for the purpose of enclosing it is the representation of a slipper consisting of an open top flexible casing 22, having its front formed with a transversely extending opening to expose the foot portion 11. If desired the casing 23 can be detachably secured by stitching to either covering 3 or 4.

By way of example, the doll is illustrated of the female type, but it is obvious that the dress mounted on the doll body can be other than that as shown, for example the doll body can be provided with clothes to represent a male infant.

As the doll is of the flat type, several thereof can be readily packed in a travelling case without taking up the ordinary space occupied by a doll having a body of the rounded type.

It is thought the many advantages of a toy doll constructed in accordance with this invention, can be readily understood, and although the preferred construction of the doll body is as illustrated and described, yet it is to be understood that changes in the details of construction can be had which will fall within the scope of the invention as claimed.

What I claim is:—

1. A doll comprising a body portion flat throughout and formed from a unitary flat base of paper stock having a fabric covering secured throughout and conforming to the shape of each face thereof, said base shaped to represent the body, a pair of spaced legs, oppositely extending arms, neck and head of

an infant, and said fabric coverings providing means for attaching thereto the wearing apparel of the doll by stitching.

2. A doll comprising a body portion flat throughout and formed from a unitary flat base of paper stock having a fabric covering secured throughout and conforming to the shape of each face thereof, said base shaped to represent the body, a pair of spaced legs, 5 oppositely extending arms, neck and head of an infant, and said fabric coverings providing means for attaching thereto the wearing apparel of the doll by stitching, one of said fabric coverings at the head portion 10 thereof having secured thereto threads to provide respectively the representation of the eyes, nose and mouth of the doll.
3. A doll comprising a body portion flat throughout and formed from a unitary flat 20 base of paper stock having a fabric covering secured throughout and conforming to the shape of each face thereof, said base shaped to represent the body, a pair of spaced legs, oppositely extending arms, neck and head 25 of an infant, said fabric coverings providing means for attaching thereto the wearing apparel of the doll by stitching, one of said fabric coverings at the head portion thereof having secured thereto threads to provide 30 respectively the representation of the eyes, nose and mouth of the doll, and a mass of hair overlapping the marginal portions at the top and sides of each fabric covering at the head of said body portion.
- 35 4. A doll comprising a body portion flat throughout and formed from a base of paper stock having a fabric covering secured throughout to each face thereof, said body portion shaped to represent an infant, said 40 fabric coverings providing means for at-

taching thereto the wearing apparel of the doll by stitching, one of said fabric coverings at the head portion of said body having secured thereto threads to provide the representation of the eyes, nose and mouth 45 of the doll, a mass of hair overlapping the marginal portions at the top and sides of each fabric covering at the head of said body portion, and open top fabric casings mounted on the foot portions of said doll 50 body and each having its outer side formed with a transversely extending opening to expose a part of the foot portion.

5. A doll comprising a body portion shaped to represent an infant, said body portion flat throughout and formed of a unitary base shaped to represent the body, a pair of spaced legs, oppositely extending arms, neck and head 55 of an infant and having secured throughout each face thereof a fabric 60 covering providing means for attaching wearing apparel to said body portion.

6. A doll comprising a body portion flat throughout and including a one piece flat base shaped to represent the head, neck, 65 a pair of arms, body, a pair of legs, hands and feet of an infant, said body portion further including and having secured throughout each face of the base a fabric covering corresponding in contour to the 70 shape of the base and providing means for attaching wearing apparel to said body portion, one of said coverings having connected therewith at the head portion thereof a series of sets of threads to represent respectively the eyes, nose and mouth of the doll. 75

In testimony whereof, I affix my signature hereto.

GLADYS RUSH.
